UNITED STATES PATENT OFFICE.

HENRY D. OBERDORFER, OF CHAMPAIGN, ILLINOIS.

PORTABLE BLEACHER.

Application filed August 1, 1923. Serial No. 654,970.

This invention relates to a portable stand or bleacher construction, and one of the objects of the invention is to simplify and standardize the equipment so that the parts 5 are interchangeable and easily and quickly assembled or taken down. A further object of the invention is to provide hanger supports which are so attached to the stringers that they will not weaken the stress and 10 strain edges thereof. Other objects of the invention will appear hereinafter.

In the accompanying drawing, Fig. 1 is a perspective of a section of a bleacher embodying the present invention; Fig. 2 is a 15 section showing the construction; Figs. 3 and 4 are top and end views respectively illustrating a hanger support; Fig. 5 is a perspective further illustrating the construction and application of the hanger supports; 20 and Fig. 6 is a perspective illustrating the end of one of the stringer connectors.

In erecting a stand of this kind it is highly desirable that the parts may be assembled quickly and accurately, and also that as 25 many of the parts as possible be similar or interchangeable so that the least chance may be afforded for making an error in assembling. When wood stringers are used it has been found that the attachment of the 30 rail supports to the lower edges of the stringers tends to weaken the edges. Furthermore the foot board supports if attached by means of screws or bolts to the bottom edges are more likely to pull out than if 35 they are connected through the stringer itself or hooked over the top therof. In the present invention these objections are overcome by connecting the foot board supports upon the longitudinal center line of the 40 stringer or hooking them over the upper edge, or both.

As shown in Fig. 1, the invention is applied to a pair of spaced wooden stringers 1, but it is applicable equally well to metal 45 stringers. The stringers are spaced apart and held in upright parallel position by means of plates 2 attached on opposite sides of the stringers by fastening bolts 3 with headed projections 4 extending outwardly 50 from the face of each plate. At the ends of a spacing bar 5 are rigidly attached angular heads 6 having notches 7 and 8 adapted to be engaged over the headed projections 4. These notches are simply placed over the 55 heads 4 of adjacent stringers, and the string-

ers will be locked in upright parallel spaced position.

Seats 9 are supported on top of the stringer by means of brackets 10 the legs of which are of unequal length so that the 60 seat board will be held in substantially horizontal position and prevented from displacement by means of the front and rear bends 11 and 12.

Foot boards 13 are supported below the 65 stringers by means of hanger supports 14 each of which comprises a straight portion for carrying the foot board 13, and at the ends of this straight portion are unequal legs 16 and 17 inclined slightly to the straight 70 portion 15 and the extremities each twisted substantially at right angles so that the twisted extremities will fit flatly against the opposite sides of a stringer 1 so that a fastening device 18 can be inserted through 75 the leg portion and through the stringer at about the transverse center of the stringer. The extremities 19 and 20 of these legs 16 and 17 are bent oppositely at right angles to engage over the top of the stringer to which 80 they are applied, and a fastening device 21 is inserted therethrough into the upper edge of the stringer.

With this construction it is obvious that the lower strain line of the stringer is not 85 weakened by the insertion of fastening devices and as the transverse center of a stringer of this kind has practically no stress or strain lines, the stringer is not weakened by the insertion of the fastening devices 18. 90 As the fastenings for both the hangers 15 and the seat brackets 10 are all on the upper edge of the stringer, they are easily secured in place.

In taking down the bleachers it is necessary only to remove the seat and foot boards and then to disconnect the heads 6 of the cross connecting rails from the headed bolts. The construction is therefore easily assembled, may be quickly taken down, and 100 occupies a minimum space when taken down, and is easily conveyed from one place to another, therefore making an ideal portable construction.

I claim:

1. In portable bleachers, the combination 105 with a pair of stringers supported at intervals, of means for locking them spaced apart in upright parallel position, seat and foot boards therefor, and a plurality of supports 110

and hangers each attachable at the upper edges of the stringers for supporting the seat and foot boards respectively.

2. In a bleacher construction, a foot board hanger support for attachment to a stringer, the support having an intermediate straight portion to extend below and at an angle to the stringer and twisted ends of the same width of material but of unequal length adapted to fit flatly against opposite sides of a stringer to which it is attached.
3. In a bleacher construction, a foot rail hanger comprising a metal support made of strip material having an intermediate straight portion for the attachment of a foot board, and right angled arms unequal in length which are twisted substantially at

right angles so they will fit flatly against the opposite faces of a stringer to which they are attached, the extremities of the arms being bent to fit over and engage the upper edge of the stringer.

4. In a bleacher construction, an inclined stringer, a foot board support comprising a bracket made of strip metal with a straight portion and unequal twisted arms, the extremities of which are bent oppositely inward to engage over the upper edge of the stringer and the arms engaging the opposite upright faces thereof, and fastening means for connecting the arms to the stringers along the center line, where stress and strain are at the minimum.

HENRY D. OBERDORFER.
